(57) **CLAIM**

The ornamental design for a pendant, as shown and described.

DESCRIPTION

FIG. 1 is a top view of the pendant.

FIG. 2 is a left side view of the pendant.

FIG. 3 is a front view of the pendant.

FIG. 4 is a right side view of the pendant.

FIG. 5 is a bottom view of the pendant; and,

FIG. 6 is a rear view of the pendant.

The broken lines illustrate portions of the pendant which form no part of the claimed design.
